DESIGN FOR A DISPLAY MANNIKIN

Lillian L. Greneker, New York, N. Y.

Application November 12, 1937, Serial No. 72,816

Term of patent 7 years

To all whom it may concern:

Be it known that I, Lillian L. Greneker, a citizen of the United States, residing at New York city, county and State of New York, have invented a new, original, and ornamental Design for a Display Mannikin, of which the following is a specification, reference being had to the accompanying drawing, forming part thereof.

Fig. 2 is an enlarged side elevational view thereof with a portion of the head (in dotted lines) broken away; and

I claim:

The ornamental design for a display mannikin, substantially as shown.

LILLIAN L. GRENEKER.
